Primary Examiner — Barbara Fox(74) *Attorney, Agent, or Firm* — Christie, Parker & Hale, LLP(57) **CLAIM**

The ornamental design for a portable display, as shown and described.

DESCRIPTION

FIG. 1 is a front perspective view of a portable display showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a front perspective view thereof in an unrolled state. The broken lines in the drawings are for illustrative purpose only and form no part of the claimed design.
